STOCK STRETCHER

Peter Lesteshen, Cleveland, Ohio, assignor to The Yoder Company, Cleveland, Ohio, a corporation of Ohio
Filed Aug. 24, 1959, Ser. No. 835,486
13 Claims. (Cl. 153—35)

This invention relates generally as indicated to a stock stretcher and more particularly to a stock stretcher especially adapted to stretch or pre-stress strip material prior to a subsequent embossing operation.

Embossing or working operations often result in the rupturing of the stock strip material due to stress concentrations occurring in such operation. I have found that if the stock is sufficiently pre-worked or deformed in such a manner as to increase the length thereof in certain areas, such rupturing as the result of a subsequent forming operation does not occur. Thus a stretching or deforming mechanism that will alleviate this problem of rupturing due to such stress concentrations occurring in the subsequent embossing operation is to be highly desired.

It has been attempted to increase the workability of sheet strip material prior to a subsequent working operation by passing such strip through a staggered roll assembly. A device of this type may be seen in the patent to Montgomery 2,153,811. This pre-working of such sheet material is generally inadequate for forming deep embossments such as the diamond patterns which are used to strengthen and rigidify flat sheet material for modern unitary roofing and floor decking materials used in modern construction methods.

I have found that in order effectively to pre-work the strip material so that the subsequent embossing operations will not cause ruptures in the material, it is necessary longitudinally to stretch such material with the maximum area of stretch generally being positioned in the area of such strip subject to the maximum deformation as the result of the embossing operation. Such stretching can preferably be accomplished by subjecting this particular area of the strip to a path of travel greater than the path of travel of such other portion of the strip not subject to the subsequent working operation.

It is accordingly a principal object of my invention to provide a mechanism which will adequately produce sheet material having deep embossments therein without rupturing or damaging such product in any way.

It is a further principal object of my invention to provide a mechanism that will adequately stretch such stock in the predetermined area to enable such subsequent embossing operation to be properly performed thereon.

It is yet another object of my invention to provide a mechanism that will elongate a portion of metal strip which will distribute the elongation evenly along the length of the strip while controlling the width of such elongated portion.

It is still another object of my invention to provide a mechanism that will discriminately stretch metal strip in the desired manner and location that can quickly and easily be threaded when the coil stock is exhausted.

It is a further object of my invention to provide a simplified roll stand that will properly stretch longitudinal portions of strip stock in which the pressures of the rolls controlling the paths of movement of various transverse portions of such strip can readily be controlled.

Other objects and advantages of the present invention will become apparent as the following description proceeds.

To the accomplishment of the foregoing and related ends, the invention, then, comprises the features herein-after fully described and particularly pointed out in the claims, the following description and the annexed draw-

2

ings setting forth in detail certain illustrative embodiments of the invention, these being indicative, however, of a few of the various ways in which the principles of the invention may be employed.

5 In said annexed drawings:

FIG. 1 is a side elevational view of my stock stretcher showing its relation to the embossing stand;

FIG. 2 is a front elevation of my stock stretcher partially in section;

FIG. 3 is a top plan view of my stretcher shown in FIG. 2;

FIG. 4 is a vertical section taken generally on the line 4—4 of FIG. 2;

15 FIG. 5 is an elevation illustrating the profile of my upper roll;

FIG. 6 is a view similar to FIG. 5 illustrating the profile of my lower rolls;

FIG. 7 is a somewhat schematic plan view illustrating the rolls in relation to the stretched and unstretched areas of the strip and the subsequent embossments therein; and

20 FIG. 8 is a view similar to FIG. 7 illustrating a slightly modified roll arrangement producing a different stretching pattern for strip embossment.

Referring now to FIG. 1, the strip S passes through a forming station which can, for example, flange the edges thereof and then through my stock stretcher generally indicated at 1. From the stock stretcher the strip passes through the embossing stand generally indicated at 2 which comprises upper and lower embossing rolls 3 and 4, such embossing and forming stations being of a generally conventional nature.

Referring now to FIGS. 1 through 4 inclusive, it will be seen that my stock stretcher comprises a lower roll support or bracket 5 mounted on a base plate 6 which can be secured to the floor by a plurality of bolts 7. The lower roll bracket may be preferably of welded steel construction and includes two front face plates 8 and 9 mounting thereon adjusting screw supports 10 and 11 respectively for a purpose hereinafter described. At the right hand portion of the lower roll bracket as seen in FIG. 1, there is secured support plates 12 and 13 upwardly terminating in bifurcated pivot blocks 14 and 15 having secured therein aligned pivot pins 16 and 17 respectively for a purpose subsequently to be described.

40 45 The lower roll bracket also includes a support bed plate 18 welded to three vertical supports 19, 20 and 21. These vertical support plates extend across the roll stand and support on each end thereof bearing plates 22 and 23 in which are positioned the lower supporting roll shafts 24, 25 and 26 of my stock stretcher.

50 55 Each side of the roll stand is provided with gussets or supporting ribs 27 and 28 as shown in FIG. 3, thus firmly to support the plates 8, 9, 22 and 23 in their proper normal positions. It will now be seen that the rolls are supported in bearing plates 22 and 23 and that bed plate 18 extends between such bearing plates and that the three vertical supports 19, 20 and 21 firmly maintain such bed plate 18 in its proper horizontal position.

Referring now to FIG. 2, it will be seen that my lower 60 supporting rolls are positioned in the side plates 22 and 23 and extend through end supporting blocks 30 and 31 resting on bed plate 18 as well as spaced supports 32, 33, 34 and 35. Journalled on the shaft 26 are five supporting rolls 36, 37, 38, 39 and 40 having the profiles shown 65 in FIG. 2, such shaft 26 and rolls 36 through 40 generally comprising a supporting roll assembly. Such rolls are mounted for rotation about the roll shaft 26 which is maintained in its proper horizontal position by the supports 30 through 35 inclusive secured to bed plate 18. The rollers mounted on shaft 24 are identical in form to the rollers shown in FIG. 2. As illustrated, washers may be 70 employed to center the support rollers between the sup-

ports and to enclose the bearings for the rolls which may be roller, slide or ball bearings.

The roll shaft 25 is positioned slightly above the centers of roll shafts 24 and 26 and is of a slightly smaller diameter. However, the profile configuration of the five supporting rolls thereon are substantially the same as the rolls 36 through 40 inclusive.

Also rotatably secured in the plates 22 and 23 are my lower working rolls 41 and 42. These rolls are secured in apertures in the plates and held therein by retainer plates as shown at 43 in FIG. 1. In this manner, the lower working rolls are free to rotate on the supporting backup rolls and yet are firmly held in the correct longitudinally aligned position by such retainer plates.

My upper roll bracket is generally shown at 50 and has depending from the front thereof two apertured ears 51 and 52 which are so spaced to be received in the bifurcated portions of the support blocks 14 and 15 whereby the pins 16 and 17 may be secured therethrough so that my entire upper roll bracket 50 may pivot about the axis of such pins 16 and 17. The upper roll bracket is made preferably of reinforced welded steel construction as shown more clearly in FIG. 4 and comprises a top plate 53 on which is secured a cam enclosure 54. Such cam enclosing includes an enlarged top bearing plate 55 designed to rest on cam 56. At the rear end of the top plate 58 is another enlarged bearing plate 57 which cooperates with the plate 55 so that the entire upper roll bracket assembly may be pivoted about the axis of the pins 16 and 17 by the manipulation of the cam 56 about its eccentric axis. The manipulation of the cam to adjust the upper roll bracket will be subsequently described.

The upper roll bracket includes support plates 58 and 59 spaced from the top plate by a series of transversely vertically extending plates 60, 61, 62, 63 and 64. Plate 61 is welded between plates 58 and 59 and extends downwardly to form the front side of the top roll housing. Plates 63 and 64 are secured between the bearing plate 57 and the support plate 59 rigidly to form the rear of my top roll assembly. Secured to the ends of the plates 61, 62, 63 and 64 are my upper bearing plates 65 and 66 in which the shafts 67 and 68 of my upper backup rolls are secured. The shafts 67 and 68 are also secured in supports 69, 70, 71 and 72 secured to the lower side of plate 58 in a manner similar to the supports 32 through 35 being secured to bed plate 18. Mounted on the shaft 67 are rollers 73, 74, 75, 76, 77. These rollers are each provided with bearings whereby they may rotate readily. The rollers on shaft 68 are identical in form to the rollers 73 through 77 inclusive. It can now be seen that I have provided a firm backup roll arrangement for my upper working roll. The upper working roll 78 is nested between my supporting roll assemblies and is secured in an aperture or cutout portion in each plate 65 and 66. As noted in FIG. 5, the ends of such upper roll 78 are sharply crowned or tapered as shown at 79 and 80 and the cutout portions in such plates 65 and 66 are similarly shaped such that a downward pressure on the upper roll bracket will tend properly to center the upper working roll in its prescribed position. The shafts 67 and 68 of the upper backup roll assemblies are secured in the plates 65 and 66 so that when the upper roll bracket is pivoted about pins 16 and 17, the upper working roll 78 may then be removed simply by removing locking caps secured to the bottom of plates 65 and 66. This considerably enhances the quickness with which the roll assembly may be rethreaded.

In order to adjust the upper roll bracket about the pins 16 and 17, the cam 56 is supported on cam support 80 which is in turn secured to the lower roll bracket by means of adjusting screws 81 and 82. Thus the cam 56 can properly be spaced from the lower rolls to maintain the rolls of the upper and lower brackets in the proper parallel positions so that only a subsequent ad-

justment of the cam 56 need be made to apply the proper pressure across the entire transverse portion of the strip.

The adjusting screws 81 and 82 are secured to ribs 83 and 84 respectively which are in turn secured between upright bearing caps 85, 86, 87 and 88 respectively. Positioned through such bearing caps is cam shaft 89 having squared ends 90 and 91 by which such cam shaft may readily be rotated by a wrench, crank or power driven device, for example.

As seen in FIG. 2, the cam 56 extends entirely between bearing caps 86 and 87 to be enclosed by the plates 55 and 57 mounted on the top of the upper roll bracket. In this manner, the proper adjustment of the screws 81 and 82 will align the axes of the various supporting and work rolls in the necessary parallel position. As soon as the rolls are properly aligned, only subsequent adjustments of the cam need be made to apply the proper deformation to the strip S. Thus the upper working roll may readily be lowered into pressure engagement with the strip S.

If desired, my stock stretcher may be secured directly to the embossing stand by bolts 92 passing through the plates 8 and 9. Bolts 93 and 94 may also be employed passing through elongated slots 95 and 96 in the cam support 80 thus permitting movement of such cam support relative to the embossing stand whereby the required adjustments may be made through screws 81 and 82. It is noted that such screws are also provided with squared ends 97 and 98 to effect more evenly a rapid adjustment thereof.

Referring now to FIG. 5 and 6, I illustrate the profiles of my working rolls. FIG. 5 illustrates the profile of my upper roll which may be, for example, approximately 15½ inches long and includes a center right circular cylindrical portion 100 and which tapers through an angle of approximately 2° to the sharp bend 101, such roll terminating in a crowned portion 79 of the same general configuration as the recess in bearing plates 22 and 23. The opposite end of the roll is, of course, allochirally the same and terminates in crowned portion 80.

There are two lower working rolls 41 and 42 and both have the similar right circular cylindrical center portion 102 and also taper at approximately 2° to an elongated portion 103 which terminates in the bearing plates 22 and 23. Again, the bearings for the work rolls are such that they may be supported firmly by the backup rolls having the configuration shown more clearly in FIG. 2. Thus, the center backup rolls 38 and 75 are rectilinear rolls which mate with the right circular cylindrical center portions of each of the respective work rolls. The other backup rolls, of course, have the same taper as the work rolls thus firmly to provide the proper nest therefor. It can be seen that the curvilinear contour of the working and backup rolls substantially eliminates any end thrust problems that may be involved.

Referring now to FIG. 7, it will be seen that the work rolls provide a pass in which the strip S is forced to travel through a greater distance at certain portions thereof than at the other portions. Consequently, in the illustrated embodiment, the maximum stretch of the strip will be obtained in the center at the area generally shown as 104 and the sides 105 and 106 will not substantially be subject to any deformation or stretching. As a result, deep diamond shaped embossments as those shown at 107 may subsequently be made in the stretched area of the strip 104 without the danger of such strip rupturing. It can now be seen that the rolls may be forced together with a degree of pressure such that the width of the stretched area 104 may be controlled. Thus if the rolls are firmly pressed together, the entire width of the strip may be forced through paths of various lengths thus to varying degrees stretching the entire width of a strip. It is noted that such stretching results only by portions of the strip moving through a longer path of travel with respect to other portions of the strip. The pressure of the working rolls limits most of the stretch of the stock

to an elongation rather than transversely of the strip. As seen in FIG. 8, the work rolls may take any desired configuration and I have illustrated as an example, rolls of a sinusoidal profile that stretch or elongate two spaced areas of the strip S as shown at 108 and 109. In this manner, embossments 110 of a different pattern may be employed on the strip. Of course, such pre-stretching can be applied to many more embossing problems than are illustrated in the two examples schematically shown in FIGS. 7 and 8. The possibility of varying the stretched area and the embossment subsequently formed can infinitely be varied.

It will now be seen that I have provided a means simply and easily to stretch or deform sheet material to enable the next operation thereon to be successfully applied.

Moreover, with use of my unique cam adjustment, I can quickly release all of the pressure on the top roll whereby such top roll may easily be withdrawn for easy rethreading of new stock. Moreover, the single adjustment of the cam operated upper roll assures that the top roll is parallel to the lower rolls and once so set with the adjusting jack screws, the cam operation will not move the rolls out of such parallel position.

Whereas I have shown a cluster mill stand in which neither the working nor backup rolls are driven, the strip preferably being pulled through the stand under tension, it will readily be understood that either or both may be driven through a convenient power source.

Other modes of applying the principles of the invention may be employed, change being made as regards the details described, provided the features stated in any of the following claims or the equivalent of such be employed.

I, therefore, particularly point out and distinctly claim as my invention:

1. A stretching mechanism for strip material comprising a pair of lower working rolls and a single upper working roll, means to move the upper working roll into a nested position between the lower working rolls, said working rolls having axially corresponding enlarged portions to define a substantially longer path for the transverse portion of the strip passing therewith, and backup rolls for said working rolls, said backup rolls having a mating profile configuration with said working rolls to support said working rolls uniformly axially thereof.

2. A mechanism as set forth in claim 1 including pressure means to force the working rolls into nested relationship to stretch the strip material passing therethrough.

3. A mechanism as set forth in claim 2 wherein said pressure means comprises a cam mechanism to force the upper working roll down against the strip between said lower working rolls.

4. A mechanism as set forth in claim 3 wherein said upper working roll is pivotally mounted and said cam forcibly pivotally moves said upper working roll against the lower working rolls to stretch the strip as it is passed through said working rolls.

5. A strip stock stretcher comprising a base, two lower working rolls journaled in said base having a curvilinear longitudinal profile, backup roll assemblies also journaled in said base uniformly longitudinally supporting said lower working rolls, an upper roll stand pivotally mounted on said base and an upper working roll journaled therein having a similar curvilinear profile, upper backup roll assemblies journaled in said upper roll stand longitudinally evenly to apply pressure against said upper working

roll, pressure applying means operatively connected to said upper roll stand to swing said upper roll stand about such pivot to force said upper working roll into a nested relation between said lower working rolls.

5 6. A strip stock stretcher as set forth in claim 5 wherein said lower working rolls have a central right circular cylindrical portion and tapering end portions terminating in smaller diameter right circular cylindrical portions, and said upper working roll has a central right circular cylindrical portion tapering to crowned end portions, said center portions of said working rolls being of equal length.

10 7. A stock stretcher as set forth in claim 5 wherein the maximum diameter portions of said working rolls are substantially juxtaposed.

15 8. A stock stretcher as set forth in claim 7 wherein said working rolls have a sinusoidal profile such that the working rolls have axially spaced respective corresponding maximum diameter portions effective to stretch stock passed therethrough only at such transverse portions of the strip passing through said maximum diameter portions of the working rolls.

20 9. A stock stretcher for strip material and the like comprising a base including a lower roll stand, an upper roll stand pivotally mounted thereto, pressure applying means connected to said upper roll stand, and roll cluster means journaled in said upper and lower roll stands to define a tortuous path for certain transverse portions only of the strip passing therethrough, said pressure applying means comprising a cam bearing against said pivotally mounted upper roll stand.

25 10. A stock stretcher as set forth in claim 9 wherein said cam means is mounted on a horizontally extending shaft journaled in supports vertically adjustable with respect to said lower roll stand.

30 11. A stock stretcher as set forth in claim 10 wherein said cam shaft is horizontally alignable with respect to said lower roll stand.

35 12. A stretcher as set forth in claim 11 wherein said roll clusters comprise two curvilinear profile rolls in said lower roll stand and a single curvilinear profile roll in said upper roll stand, said rolls being so positioned that the maximum diameters thereof are axially juxtaposed.

40 13. A stretcher as set forth in claim 12 including backup rolls for said upper and lower working rolls, said backup rolls including a plurality of axially spaced bearing rolls having curvilinear surfaces of a mating configuration with the respective portions of said working rolls.
